UNITED STATES PATENT OFFICE.

JOZEF LEJA, OF FALLENTIMBER, PENNSYLVANIA.

COIN-ASSORTING APPARATUS.

1,346,457.

Specification of Letters Patent. Patented July 13, 1920.

Application filed December 17, 1919. Serial No. 345,519.

To all whom it may concern:

Be it known that I, JOZEF LEJA, a citizen of the United States of Poland, residing at Fallentimber, in the county of Cambria and 5 State of Pennsylvania, have invented certain new and useful Improvements in Coin-Assorting Apparatus, of which the following is a specification.

This invention relates to certain new and 10 useful improvements in coin-assorting apparatus particularly adapted to separate and deliver into separate compartments, coins of different denominations in a quick and efficient manner.

15 Briefly described, the invention embodies a casing having a hopper into which coins of different denominations are simultaneously put, conveying means onto which the coins fall from the hopper and by means 20 of which the coins are transferred singly to a chute construction which is so devised as to effect the delivering of the coins into certain compartments according to the denominations of the coins.

25 The invention resides in certain specific details and the combination and arrangement of parts as will be hereinafter more fully described and pointed out in the appended claim.

30 In the accompanying drawings, wherein like reference characters designate corresponding parts throughout the several views,

Figure 1 is a front elevational view of a 35 coin-assorting apparatus constructed in accordance with the present invention,

Fig. 2 is a top plan view thereof,

Fig. 3 is a view, partly in elevation and partly in central vertical section of the 40 device shown in Fig. 1,

Fig. 4 is an enlarged fragmentary sectional detail view, partly broken away, and taken substantially upon line IV—IV of Fig. 3,

45 Fig. 5 is a fragmentary detail view showing the yieldable coin-supporting members of the conveying means in plan and the driving sprocket for the endless member of the conveying means,

50 Fig. 6 is an edge elevational view of a fragment of the endless member and the coin-supporting members carried thereby and

Fig. 7 is a sectional detail view taken substantially upon line VII—VII of Fig. 3.

Referring more in detail to the several views, the present apparatus embodies a substantially rectangular casing 5 having a built-in hopper 6 at the top thereof, and provided with a removable drawer 7 in the bottom portion thereof, which drawer is divided into a plurality of compartments 8, 9, and 10 adapted to have coins of different denominations delivered thereto in a manner and by a means to be presently described.

The hopper 6 is open at its bottom so that coins which are placed therein will fall on the endless member 11 of the conveying means. The endless member 11 is preferably in the form of a belt and has, at suitable intervals, a plurality of resilient plates 12 secured thereto. The plates 12 are preferably flat at one end as shown in Fig. 6 and rivets 13 are passed through this flat end and through the endless member 11 to fasten the plates in position.

A slightly similar but smaller resilient plate 14 is fastened upon each plate 12 by means of the rivets 13, and the flat or fastened ends of the plates 14 are turned outwardly as at 14' so as to form abutments against which the coins rest for insuring movement of the coins with the endless member 11 when the same is caused to travel in the direction indicated by the arrow *a* in Fig. 3. The endless member 11 passes around suitable sprocket drums 15, one of which is journaled in the conveyer housing 16 by means of a shaft 17, and the other of which is journaled in the casing 5 above the drawer 7 by means of a shaft 18 which is provided with a crank 19 exteriorly of the casing 5 so that the drum 15 carried by said shaft 18 may be manually rotated for causing movement of the endless member 11 when desired.

In order to insure movement of the member 11 upon rotation of the drums, the latter are provided with suitable spurs 20 which penetrate said member 11 and provide a somewhat positive drive therefor.

As the coins are fed into the hopper 6, the same pass to a plurality of springs 21 which are fastened to the housing 16 and which have their free ends positioned so as to bear against the plates 14 as the latter pass therebeneath. These springs 21 prevent more than one coin passing at a time so that each plate 14 will have only one coin resting thereon.

The plates 12 and 14 may yield toward

the endless member 11 slightly under the pressure of the springs 21 if the thickness of the coin so demands.

An inclined guard plate 22 is positioned 5 beneath the return flight of the endless member 11 and has its upper end arranged close to the endless member so that coins are forced to drop from the conveying means onto the upper surface of the inclined chute 10 23 which is disposed beneath the guard plate 22 in spaced relation to the latter.

The chute 23 is extended downwardly to a point above the compartment 9 of the drawer 7 as shown in Fig. 3 and has a suitable trough member 24 secured to its lower end so that coins which pass from said trough, will, through momentum gained while passing down the chute 23, fly onwardly and downwardly into the compartment 8. The chute 23 is provided with an elongated slot 25 substantially midway between its ends which is of such size as to prevent coins of a certain denomination from passing therethrough, and this denomination of coin is the one which will be delivered to compartment 8 of drawer 7. All coins which are smaller will pass through slots 25 onto a second chute 26 which is disposed beneath chute 23. Chute 26 is also 20 provided with a slot 27 adjacent its end which is of such a size as to prevent coins of another denomination from passing therethrough and to thereby cause the same to pass from the lower end of said chute 30 26 into compartment 9 of the drawer 7.

Smaller coins will be permitted to pass through slot 27 and will strike the deflector 28 which is fastened to the chute 26 and will thereby be directed into compartment 10.

It is believed that the construction and operation as well as the practical nature of the present invention will be readily understood and appreciated from the foregoing description.

While the forms of the various parts and the combination and arrangement of parts shown and described are believed to be preferable, it is nevertheless to be understood that minor changes may be made without departing from the spirit and scope of the invention as claimed.

Having thus described my invention what I claim as new and desire to secure by Letters Patent is:—

In a coin-assorting apparatus, means for delivering coins from a point of supply to a point of separation including an endless member having a plurality of resilient plates secured thereon, each adapted for the reception of a coin, abutments carried by said plates adapted to engage the coin for insuring movement of the latter with the endless member, means disposed above said endless member to prevent the passage of more than one coin at a time past the same, said last-named means including a spring arranged to bear upon said resilient plate.

In testimony whereof I affix my signature.
JOZEF LEJA.
